MAGAZINE FOR THE STORAGE OF ARTICLES

Spencer L. Childers, Fresno, Calif., assignor, by direct and mesne assignments, to The Vendo Company, Kansas City, Mo., a corporation of Missouri

Application February 21, 1955, Serial No. 489,319

6 Claims. (Cl. 221—67)

The present invention relates to magazines for the storage of articles of substantially uniform size and shape and more particularly to such magazines in which articles are releasably retained in vertically staggered overlapping stacks in the manner typified by the vending machine of the patent to Hoffman No. 1,205,094 and to a somewhat lesser extent by the dispensing machine of the patent to Hoopes et al. 1,711,021. While the storage of vendable articles in such interlaced or interlocked stacks has been well known, magazines suited to such storage have not heretofore been able to accommodate articles of appreciably different size or shape from that originally contemplated without complete reconstruction.

While the present invention is in no sense limited to application to bottle vending machines nor even to vending machines, it was developed as a solution to problems encountered in the vending of refrigerated bottle beverages and is conveniently illustrated in connection with such machines.

The present application is a further development of the invention comprising the subject matter of a co-pending patent application of the applicant and Lawrence C. Tober, filed November 1, 1954 and designated by Serial No. 465,779. In that application, the importance of providing a compact, comparatively shallow vending machine to enable its convenient positioning in busy, crowded and/or congested areas is pointed out. The vending machine described in that application provides generally for supporting pairs of columns of vendable bottles in vertical, staggered relation with the bottles in adjacent columns being in overlapping supporting relation to super-adjacent bottles in opposite columns. In addition, oscillatable rockers are provided beneath the pairs of columns for supporting the columns and for sequentially releasing the bottles for discharge incident to customer manipulation of a coin conditioned vending mechanism.

Although the above briefly described construction has been found highly effective in handling bottles and the like of predetermined size, it is not adaptable to different sizes and shapes without reconstruction.

An object of the present invention is, therefore, to provide a storage magazine for articles of substantially uniform size and shape which is adjustable to accommodate various sizes and shapes of such articles.

Another object is to provide an improved adjustable mechanism for controlled retention and dependable dispensing of articles arranged in vertically staggered overlapped stacks.

Another object is to provide a vending machine adjustable to accommodate vendable articles of varying sizes.

Another object is to provide a vending machine of minimum front to back depth so as to make possible its location in restricted areas and passages heretofore regarded as unable to accommodate vending machines and which is adapted for modification to accommodate a

2

multiplicity of substantially uniform sizes and shapes of articles.

Another object is to provide a vending machine having a magazine for containing articles to be vended which is adjustable in length and/or width.

Another object is to provide a vending machine having an upright compartment adapted to support vendable articles which has a downwardly constricted lower end portion adjustable as to degree of downward constriction.

10 Another object is to provide a vending machine in which articles to be vended are supported in vertically stacked relation, in which are provided rockable cradles adapted to support and sequentially to release the articles, and in which the cradles are adjustable to accommodate a variety of article sizes.

Other objects are to provide an improved magazine for bottle vending machines and the like which is compact and dependable in nature, which minimizes bottle damage and jarring, which is quickly and conveniently loaded, 20 which is economical to produce and operate, and which is highly effective for accomplishing its intended purposes.

These and other objects will become more fully apparent upon reference to the following description.

In the drawings:

25 Fig. 1 is a fragmentary front elevation of a vending machine embodying the principles of the present invention having a forwardly disposed access door of the vending machine removed for illustrative convenience.

30 Fig. 2 is a somewhat enlarged fragmentary horizontal section taken on line 2—2 of Fig. 1 but with the access door in closed position.

Fig. 3 is a somewhat enlarged fragmentary vertical section taken on line 3—3 of Fig. 2.

35 Fig. 4 is a somewhat enlarged horizontal section taken on line 4—4 of Fig. 3.

Fig. 5 is a somewhat enlarged vertical section taken on line 5—5 of Fig. 3 with portions broken away for illustrative convenience.

40 Fig. 6 is an enlarged fragmentary vertical section taken on line 6—6 of Fig. 2.

Fig. 7 is a somewhat enlarged fragmentary rear elevation of a portion of the vending machine as viewed from the rear of Fig. 3 or the top of Fig. 4.

45 Fig. 8 is a somewhat enlarged fragmentary front elevation of a structural detail of the present invention.

Fig. 9 is a section taken on line 9—9 of Fig. 8.

Referring more particularly to the drawings:

As an illustrative environment for the magazine of the 50 present invention, a vending machine 10 is shown in Figs. 1 and 2 having an insulated cabinet 11 defining a refrigerated compartment 12 to which access is gained through an opening 13. The cabinet includes insulated side walls 14, a rear wall 15, and a top wall 16. The cabinet provides a lower portion 17 wherein is mounted a refrigerating or heat exchanging unit, not shown, which is adapted to cool the interior of the cabinet. Brackets 18 are attached to, and are inwardly extended from, the side walls of the cabinet adjacent to the back thereof for 55 mounting purposes to be described subsequently in greater detail.

An insulated door 19 is mounted on the cabinet 11 by hinges 20 for movement between opened and closed positions relative to the access opening 13. A seal 21 is provided between the door and front edges of the side walls 13 in the usual manner to exclude warm air externally of the cabinet and to retain refrigerated air therein. The door has an insulated wall 22 and an outer sheet-metal wall 23 defining a space 24 intermediate said walls.

65 70 An auxiliary door 25 for the space 24 is mounted by means of a hinge 26 in the door 19. The auxiliary

door provides a recess 27 rearwardly extended from the front surface thereof. Although forming no essential part of the present invention, a coin responsive mechanism 28 is mounted in the space 24 within the door 19 and is in coin receiving relation to a coin slot, not shown, accessible from exteriorly of the machine. As is the usual operation, the coin mechanism renders the vending machine operable upon receipt of a coin or coins of predetermined acceptable denomination.

Although the foregoing represents a convenient operative environment for the present invention, such environment is not to be considered as limiting the use of the present invention but only to exemplify such use.

Referring more particularly to Figs. 3 to 7, inclusive, but with continued reference to Figs. 1 and 2, a support frame 30 is mounted on the brackets 18 in a manner to be described and includes a lower chassis 31 and a removable top 32 adapted for attachment to the chassis. The top provides a plurality of transverse partition walls 33 disposed in horizontally spaced parallel relation to each other and to the side walls 14. For descriptive convenience, the partition walls hereinafter will be referred to in relation to their location in the support frame, that is, outer, inner and innermost partition walls. Each of the partition walls has front and rear inturned flanges 34 and is provided with an upwardly elongated cut-out opening or slot 35, as best seen in Fig. 5. Front and rear elongated substantially horizontal braces 36 and 37 are attached along the front and rear flanges of the partition walls, as shown in Figs. 1 and 2, in order to maintain such walls in fixed transverse relation.

The chassis 31 includes a lower rear plate 40 providing a lower section 41, a rearwardly perpendicular horizontal ledge 42 and an upper section 43. The chassis further includes a front plate 44 having the same height as, and being in substantially parallel relation to, the lower section of the rear plate. A pair of side plates 45 interconnect the rear and front plates.

The chassis 31 and the top 32 are releasably mounted in the cabinet 11 on the brackets 18, as above stated. For this purpose, as shown in Figs. 1 and 2, angle bars 50 are provided on the side plates 45 of the chassis in overlaying relation to the brackets 18 and are secured to their respective brackets by bolts 51 passed therethrough and screw-threadably engaged in their respective brackets. Thus, the entire support frame is connected or disconnected from the cabinet merely by the attachment or release of bolts 51. A total of four are normally employed.

The chassis 31 provides a plurality of transverse partition plates 55 intermediate and parallel to the side plates 45. By reference to Figs. 3 and 5, it will be noted that when the top 32 is placed in position on the chassis, the rear brace 37 is in spaced overlying relation to the lower rear plate 40, the outer partition walls 33 are in coplanar relation with the side plate 45 and the inner partition walls 33 are in coplanar relation with the partition plates 55. In this manner, a plurality of compartments 56, 57, 58 and 59 and a central space 60 are defined between the spaced partitions of the support frame 30 and constitute the magazine or magazines of the vending machine. The chassis also provides a plurality of arcuate kidney-shaped slots 61 individually disposed in the lower section 41 of the rear plate 40 beneath each of the compartments for a purpose soon to be described.

A plurality of U-shaped spacer channel members 65 are rigidly secured outwardly on the outer partition walls 33, between the inner partition walls and inwardly on the innermost partition walls, as best seen in Figs. 2 and 4. It is to be noted that the spacer channel members are in upright substantially vertical position and preferably, are provided in spaced face-to-face paired relation in the positions indicated. As indicated in Fig. 9, however, each spacer channel is provided with a threaded bore 66 and a plurality of staggered smooth latch bores 67 above and/or below the threaded bore. In this regard, it is to be noted

that the spacer channels situated between compartments 55 and 56 and compartments 57 and 58 have latch bores both above and below the threaded bore. The spacer channels outwardly of the compartments 55 and 58 and inwardly of the compartments 56 and 57 have latch openings only above the threaded bore. As will subsequently be apparent, however, the latter positioning may be reversed with the latch openings being either above or below the threaded bores in the spacer members outwardly of compartment 55 and inwardly of compartment 59. The significance of this arrangement will soon be apparent.

Inasmuch as the construction of the apparatus now to be described is the same on both sides of the central space 60, only the structure associated with the compartments 55 and 56, illustrated in Figs. 3 and 4, will be referred to in detail.

Journal pins 70 extend perpendicularly through the spacer channels 65 adjacent to the top thereof and provide substantially horizontal pivot axes parallel to the partition walls 33. Mounting arms 71 are journaled on the pivot pins on opposite sides of the compartment 56 and pairs of side panels or gates 72 are rigidly secured individually on pairs of such arms for swinging movement inwardly and outwardly of such compartment. The mounting arms provide latch plates 73 extended perpendicularly therefrom and from the panels outwardly of compartment 56 and define notches 74 adjacent to the latch plates. Each latch plate has a plurality of latch openings 75 arranged in staggered rows therein and adapted for alignment with the latch openings 67 in the spacer channels upon movement of the mounting arms inwardly and outwardly relative to the compartment 56. It is to be noted that the latch plates on the mounting arms at the right of compartment 56, when viewed from the front, are adjacent to the latch openings 67 above the threaded bores 66 in the respective channels.

Mounting arms 80 and 81 are pivotally connected on journal pins 70 on opposite sides of the compartment 57 and likewise mount side panels 82 for inward and outward pivoting movement relative to such compartment. The mounting arms 80 also provide latch plates 83 having a plurality of smooth latch openings 84 therein adapted for registration with the latch openings 67 in the respective spacer channels below the threaded bores 66 therein. The mounting arms 80 define enlarged notches 85 therein adapted to receive the latch plates 73 in the adjacent mounting arms 71 when both of the mounting arms 71 and 80 are in outward position. This relationship is best seen in Figs. 1 and 8.

The mounting arms 81 are of the same length as arms 52 and also provide latch plates 89 having a plurality of latch openings 90 therein adapted for registration with the latch openings 67 in the adjacent spacer channels 65. In addition, each of the arms 81 defines a notch 91 adjacent to the latch plate thereof.

A plurality of latch bolts 95 are provided for slidable insertion through selected latch openings 75, 84 and 90 in the latch plates 73, 83 and 84, respectively, and selected latch openings 67 in the spacer channels 65. Single retainer plates 96 provide ends pivotally connected to the spacer channels outwardly of the compartments 56 and 57 adjacent to the latch openings therein by retainer bolts 97 extended therethrough and threadably received in the respective threaded hole 66. The retainer plates are adapted to fit over the latch plates 73 and 89 and provide flanges 98 on opposite ends thereof bearing against the spacer channels. In this manner, the retainer plates hold the latch bolts in position in the latch openings.

Dual retainer plates 100 are provided for the spacer channels 65 intermediate the compartments 56 and 57 and are pivotally connected intermediate their ends to such spacer channels by threaded retainer bolts 101 received therethrough and threadably received in the threaded holes 66 in such spacer channels. The dual re-

tainer plates embrace the latch plates 73 on arms 71 at the right of compartment 56 and latch plates 83 on arms 89 so as to hold the latch bolts 95 provided therefor in the respective latch openings 75, 84 and 67. In addition, the dual retainer plates provide end flanges adapted to bear against the spacer channels 65 for maintaining the plates in proper spaced relation to the channels.

This arrangement has the advantage that only one threaded hole, as 66, need be provided in the spacer channels 65 rather than threading each of the latch openings 67. Further, the described construction provides for a more speedy adjustment of the mounting arms 71, 89 and 81 inasmuch as there are fewer bolts requiring threading manipulation. Also, the number of bolts to be matched with threaded holes is minimized. From the foregoing, it will be understood that by adjustment of the position of the mounting arms on the spacer channels, the distance between the panels 72 and 82 on opposite sides of the compartments 56 and 57 may be varied.

The partition walls 33 are also provided with upper and lower rear cut-out portions 105 and 106, as best seen in Fig. 5. The upper cut-out portions define upper edges 107 having transversely and horizontally aligned notches 108. Likewise, the lower cut-out portions have lower edges 109 with transversely and horizontally aligned notches 110.

A plurality of rear adjustable walls 115 are provided individually for the compartments 56 and 57. Each of the adjustable walls has a pair of upper laterally extended support tabs 116 and a pair of lower laterally extended support tabs 117. The rear adjustable walls are adapted to be mounted transversely intermediate the partition walls 33 with the upper tabs rested in correspondingly aligned upper notches 108 and the lower tabs rested in correspondingly aligned lower notches 110. By selection of the proper notches in these edges, the adjustable walls may be moved forwardly and rearwardly in the compartments, thus shortening or lengthening the compartments, as desired. Each of the adjustable rear walls is provided forwardly thereon with a vertically extended guide channel 118 centrally positioned between the partition walls and having a pair of forwardly extended sides or flanges 119.

As stated before, the construction of the support frame 30 adjacent to compartments 57 and 58 is identical to that above described in regard to compartments 55 and 56. Thus, laterally adjustable side panels or gates 72 and 82 and longitudinally adjustable rear walls 115 are shown adjacent to compartments 57 and 58 in Fig. 1. The basic object of this construction is, of course, to enable adjustment of the length and width of the compartment.

A pair of delivery chutes 170 each having a pair of transverse U-shaped rods 171 and 172 providing outwardly extended hangers 173 are individually mounted beneath the pairs of adjacent compartments 56, 57, 58 and 59 respectively. The rearwardmost rod 171 is substantially straight through almost its entire length while the forwardmost rod 172 has a markedly depressed central portion. Each delivery chute has a plurality of longitudinal slide rods 174 rested on and connected to the transverse rods which are extended convergently downwardly and forwardly as best seen in Figs. 1 and 3. The side plates 45 and partition plates 55 of the chassis 31 are provided with openings 175 adapted removably to receive hangers 173 to enable positioning of the delivery chute in bottle receiving position beneath the compartments.

A plurality of delivery rockers or gates 180 are mounted in the support frame 30 individually beneath each of the compartments 55, 56, 57 and 58. Each rocker provides a pair of erect end plates 181 in parallel spaced relation having horizontal rocker shafts 182 journaled in the lower section 41 of the lower rear plate 40 and the front plate 44 of the chassis 31 and therefore are ad-

jacent to the rear and front plates of the chassis. A control pin 183 is extended from each of the end plates adjacent to the lower section of the rear plate through the adjacent arcuate slot 61 in such plate for movement relative thereto.

A pair of elongated transversely angulated bars 184 are extended in parallel spaced relation between the end plates 181 of each rocker 180 in substantially ninety degree spaced relation to their respective rocker shafts 182. In this regard, it is to be noted that the bars are spaced from each other a distance greater than the maximum diameter of the bottles to be vended. A pair of transversely, downwardly concave reversible bottle supporting finger plates 185 are connected individually to the angulated bars by means of screws 186 extended therethrough. Each of the finger plates provides a pair of opposed longitudinal bottle support edges 187 and 188. Each finger plate is designed so that the distance between the bottle support edge 187 and the center of the screws 186 is greater than the distance between the bottle support edge 188 and the center of the screws. Thus, when the bottle support edges 188 are positioned inwardly of the rocker, the distance between such edges is greater than between edges 187 when the latter are positioned inwardly. Obviously, wider or narrower finger plates may be provided, as desired, to control the spacing between the inwardly facing edges thereof when attached to the angulated bars.

A shaft 190 is journaled in the upper section 43 of the rear plate 40 of the chassis 31 intermediate each pair of compartments 56, 57 and 58, 59, respectively. Eccentric discs 191 are rigidly connected to the shafts for rotation therewith. A pair of levers 192 are provided, each having one end 193 pivotally connected to an extended end of one of the control pins 183 and an opposite end providing an eccentric collar 194 rotatably fitted to one of the eccentric discs 191. It will be seen that each control pin 183 has a lever 192 in driving connection thereto which in turn, has driven connection to an eccentric disc 191 individual thereto. Washers 195 are provided on the shafts 190 between the rear plate 40 and the collars 194. Driven gears 196 are rigidly secured to the shafts 190 and snap rings 197 are fitted on the shafts 190 for holding the gears in position.

A substantially horizontal shaft 200 is journaled in the upper section 43 of the plate 40 of the chassis 31 intermediate the shafts 190 in the central space 60. A drive gear 201 is secured to the shaft 200 and is in mesh with both of the driven gears 196, as best seen in Fig. 7. A mounting plate 203 is attached in the central space between the innermost partition walls 33. A control shaft 205 is mounted horizontally in the mounting plate for rotation therein in axial alignment with the shaft 200. A clutch control mechanism, generally indicated at 206, is provided for enabling stepped progression driving connection between the shaft 205 and the shaft 200 so that rotation of shaft 205 results in predetermined angular rotation of shaft 200. Inasmuch as the details of the clutch control mechanism 206 form no part of the present invention, further description thereof is not believed necessary. However, it is to be noted that a suitable clutch control mechanism is described in detail in the prior pending application of Spencer L. Childers and Lawrence C. Tober, filed November 1, 1954, and having Serial Number 465,779.

The control shaft 205 is provided with a collar 236 secured to the shaft by a pin 237 and is in abutment with the mounting plate 203. A U-shaped receiver plate 238 is connected to the control shaft by a bolt, not shown, and suitable lockwashers, not shown, are provided on the opposite sides of the receiver plate for axially positioning the plate. The receiver plate also provides outwardly extended arms 241, each of which has a key slot 242 disposed oppositely axially from the shaft 205.

Referring to Figs. 2 and 4, it will be seen that a shaft

250 extends through the auxiliary door 25 and is journaled in a socket 251 on the inner insulated wall 22 and provides an inner end having a crank 252 thereon disposed in the space 24 in the door 19. A further shaft 253 extends through the inner wall and provides a crank 254 disposed thereon and positioned in the space 24.

An elongated link 255 provides opposite ends pivotally connected to the cranks 252 and 254. Preferably, a sealed bearing sleeve 256 is provided around the shaft 253 to maintain adequate insulation and compartment tight integrity of the cabinet 11. A key 257 in the form of a pin is fitted in the shaft 253 and is extended transversely thereof. The key is adapted for engagement with the key slots 242 in the receiver plate 238. A manipulating lever 258 is connected to the outer end of the shaft 250 and is disposed in the recess 27 in a position conveniently accessible for operation by the customer.

A plurality of bottles 259 are stacked in horizontal attitudes and in vertically staggered horizontally overlapping columns in the compartments 56, 57, 58 and 59 between partition walls 33. The bottles in each column are in vertically staggered relation with the bottles in the adjacent column and are in underlying supporting relation to their respective bottles next above in the adjacent column. The lowermost bottle in each compartment is rested on one of the bottle supporting finger plates 185 and thus the finger plates along with the partition walls 33 including adjustable side panels 72 and 82 provide support for the stacks of bottles in the respective compartments. Depending on the size of bottle or other article to be vented, the walls 33 are preferably fixed so that the width of the compartments therebetween is less than twice the maximum diameter of the bottles being vended in order to maintain proper overlapping relation of the bottles and to enable proper support of the bottles by the panels and the finger plates. It has been discovered, however, that by employing the convergently adjustable side panels or gates 72 and 82, the walls 33 may be spaced much farther and the bottles or other articles retained similar to the manner of corded wood. For descriptive convenience, the compartments are hereinafter referred to as having lower outlet or discharge openings defined by the space between the adjustable panels, and indicated at 356, 357, 358 and 359 corresponding respectively to compartments 56, 57, 58 and 59.

Operation

The operation of the described embodiment of the invention is believed to be readily apparent and is briefly summarized at this point.

Initially, the size of the discharge openings 356, 357, 358 and 359 is adjusted to accommodate the bottles 259 or the like being vended. For this purpose, the adjustable side panels 72 and 82 are moved inwardly or outwardly relative to their respective compartments so that the distance between their lower ends is less than twice the maximum diameter of the bottles. In this position the latch bolts 95 are inserted through the proper latch openings 75, 84 and 90 of the latch plates 73, 82, and 89 and through the respective latch openings 67 in channels 65. The retainer plates 96 and 100 are secured in position by threaded retainer bolts 97 and 101 to prevent removal of the latch bolts from their respective latch openings.

Next, the adjustable rear walls 115 are moved longitudinally of the compartments 56, 57, 58 and 59, respectively, to accommodate the length of the bottles 259 being vended. In this regard, it is to be noted that the upper and lower tabs 116 and 117 fit in correspondingly aligned notches 108 and 110 in the partition walls 33. The arrangement of the compartments as described is best shown in Figs. 2 and 3 wherein it is to be noted that the adjustable side panels 72 and 82 and the adjustable rear walls are positioned so as to accommodate bottles having

dimensions less than the maximum which the machine will hold.

The vending machine 10 is then loaded with bottles 259, as partially shown in Fig. 1 and the door 19 and auxiliary door 25 closed and locked in closed position. When it is desired to obtain one of the bottles, a coin, or coins, of suitable denomination is inserted in a coin slot, not shown, for deposit into the coin mechanism 28. The receipt thereof releases the shaft 253 in a well-known manner and enables the depressing of the manipulating lever 258. When the lever is depressed the control shaft 205 is rotated through the key 257 turning the receiver plate 238. Rotation of the control shaft turns the shaft 200 through the clutch mechanism 206 thereby rotating the driven gears 196 through the drive gear 201. This causes rotation of the driven gears and imparts rotational movement to the eccentric discs 191. As the discs rotate, they actuate the levers 192 to oscillate the rockers 180 by movement of the pins 183. Rotation of the control shaft 205 is permitted only through a predetermined angle as controlled by the clutch mechanism 206, fully described in the prior co-pending application, cited above. Thus, a single depression of the manipulating lever 258 is effective to discharge a bottle from one of the compartments 56, 57, 58 and 59 into one of the delivery chutes 170 and the customer then releases the manipulating lever for return to its upper position.

Inasmuch as there are four compartments 56, 57, 58 and 59 in the machine shown, from which four cradles 180 dispense bottles 259 and since it is desired to dispense only one bottle during each operational movement of the lever 258, the driven connections of the rockers to the gear 201 through the pins 183, levers 192, eccentric discs 191, and gears 196 are such that the rockers are separated as to their attitudes or positions by one-quarter of their complete operating cycle. Thus when one rocker is delivering a bottle, the next to deliver is one-quarter of its cycle from delivery position, the following rocker one-half of its cycle from delivery position and the succeeding rocker three-quarters of its cycle from delivery position. It will be obvious that any desired number of compartments may be utilized and the vending mechanism modified accordingly.

Considering the specific operation of the bottle dispensing cradles 180 by reference to Fig. 3, it is assumed that the manipulating lever 258 has just been depressed and that a bottle 259 is about to move from the compartment 56 into the associated rocker 180. It will be noted that the rocker of compartment 56 has been rocked in a counter-clockwise direction, as viewed, sufficiently that the inwardly facing, longitudinal bottle supporting edge 187 of the finger plate 185 at the right of the compartment has moved upwardly into supporting engagement with the lowermost bottle of the right column in the compartment while the bottle supporting edge 187 on the finger plate at the left has been retracted downwardly and to the left from its bottle supporting position so that the lowermost bottle of the left column is released to roll between the finger supporting edges 187 and to descend endwardly into the delivery chute 170 therebelow. The second bottle in the left column is dependably supported in wedging engagement between the left adjustable side 72 adjacent thereto and the lowermost bottle in the right column, the latter being held in proper supported position on the right finger plate by the right adjustable panel 72 adjacent thereto. In this regard, it is to be noted that the right finger plate has passed to the left of vertical alignment with the center of the right lowermost bottle. In such position, the lowermost bottle is dependably held by gravitation in position between its adjacent adjustable panel and the finger plate.

A bottle 259 is discharged from only one of the delivery openings 256, 257, 258 and 259 during a cycle of opera-

tion motivated by depressing the lever 258. Thus, as the lowermost bottle from the left column of compartment 56 is dispensed, as above described, the lowermost bottles in the left or right columns of compartments 56, 57, 58 and 59 are supported by the right finger plates 185 previously moved upwardly and inwardly thereunder.

During the next and succeeding operating cycles, the rockers 180 associated with compartments 57, 58, and 59 each move, in turn, to positions so as to dispense the lowermost bottle 259 in the right column of the respective compartments. Simultaneously, the left finger plates 185 of the particular rocker move upwardly and inwardly to support the lowermost bottle of the left column in the compartment which descends thereagainst.

It will be remembered that the foregoing description has assumed that adjustable side panels 72 and 82 are fixed at inwardly convergent positions on opposite sides of their respective compartments 56, 57, 58 and 59, as seen in Fig. 3. However, assuming that the bottles 259 employed are of a smaller or larger size the outlet openings must be readjusted, as required.

Therefore, the retainer plates 96 and 100 are removed by unthreading of the bolts 97, 101 from the threaded holes 66. This enables ready removal of the latch bolts 95 from the latch openings 75, 84 and 90 in the latch plates 73, 83 and 89 from the latch openings 67 in the spacer channels 65. The side panels are then pivoted inwardly or outwardly, as desired, relative to the respective compartments so that the distance between the side panels on each side of their respective compartments is less than twice the maximum diameter of the bottles 259 to be vended. When this position is located, the latch bolts are reinserted through the proper latch openings in the latch plates and spacer channels and the retainer plates fitted over the latch plates and the retainer bolts threaded in place.

In addition, the adjustable rear walls 115 may be adjusted in position forwardly or rearwardly of the compartments 56, 57, 58 and 59, as before. It is important that the length of the compartments, that is, the front to back dimension, be adjusted properly to fit the bottles 259. With such adjustments, the flanges 119 of the guide channels 118 always bear against the necks of the bottles and maintain them in proper longitudinal attitude in their compartments. This insures proper stacking of the bottles between the plates 72 and 82 in pairs of vertically staggered, overlapped columns.

At this time, it may be necessary to reverse the position of the bottle supporting finger plates 185 on the cradles 180 in order to narrow or widen the spacing between the inner longitudinal edges 187 or 188 of the finger plates so as to permit passage of narrower or wider bottles 257 therethrough.

After these adjustments are made, the machine may be loaded with bottles 259 of the proper size, the door 19 and auxiliary door 25 closed and locked in position whereby the machine is ready for customer operation in the same manner as described above.

From the foregoing, it will be apparent that the principles of the present invention provide for a magazine capable of handling bottles and other articles of a variety of substantially uniform sizes and shapes. The economy and efficiency which the machine permits is of great significance in the vending machine industry. In general, this has been accomplished by providing for the adjustment of the length and width of the magazines or compartments holding the bottles and in the adjustment of the cradles or gates utilized for controlling the discharge of the bottles.

Although the invention has been herein shown and described in what is conceived to be the most practical and preferred embodiment, it is recognized that departures may be made therefrom within the scope of the invention, which is not to be limited to the details disclosed herein but is to be accorded the full scope of

the claims so as to embrace any and all equivalent devices and apparatus.

Having described my invention what I claim as new and desire to secure by Letters Patents is:

- 5 1. A magazine for elongated rollable articles of substantially uniform size and shape comprising substantially erect walls for confining the articles in a stack therebetween with the articles horizontally disposed and in vertically overlapping relation, said walls defining a downwardly disposed opening, a pair of panel members connected to said walls on opposite sides of the opening and downwardly convergently extended therefrom, the panel members having lower ends defining a discharge opening therebetween and upwardly adjacent to said opening being spaced a distance less than twice the maximum transverse dimensions of the articles and more than said transverse dimensions whereby the articles are supported adjacent to the discharge opening in two substantially erect downwardly convergent stacks of alternately overlapping articles, a pair of substantially parallel bars individual to the columns positioned beneath their respective columns, movable means interconnecting the bars in fixed spaced relation sufficient for the passage of articles to be vended therebetween, and control means connected to the movable means for oscillating the movable means and carrying the bars alternately and oppositely between positions in supporting relation to their respective columns and positions laterally retracted therefrom for the passage of articles therebetween.
- 10 2. A magazine for elongated articles of a variety of substantially uniform sizes and shapes comprising means for confining the articles in a stack with the articles substantially horizontally disposed and in vertically overlapping relation, said means having a downwardly disposed opening, a pair of panel members individually pivotally mounted on said means on opposite sides of the opening and downwardly convergently extended therefrom, the panel members having lower ends defining a discharge opening therebetween, adjustable means for holding the panel members with the lower ends thereof in adjusted spaced relation whereby the panel members adjacent to the discharge opening are spaceable a distance less than twice the maximum transverse dimensions of articles to be accommodated and more than said maximum transverse dimensions whereby the articles are supported adjacent to the discharge opening in two substantially erect downwardly convergent stacks of alternately overlapping articles, a pair of substantially parallel bars individual to the columns positioned beneath the columns, movable means interconnecting the bars in fixed spaced relation sufficient for the passage of articles to be vended therebetween, and control means connected to the movable means operable to oscillate the movable means and reciprocate the bars alternately and oppositely between positions in supporting relation to their respective columns and positions retracted therefrom.
- 15 3. A vending machine comprising a cabinet, upright support means mounted in horizontal spaced relation in the cabinet defining a compartment therebetween having a lower discharge opening and adapted to confine a plurality of substantially uniform vendible articles in a stack therebetween, the articles being in vertically staggered overlapping relation, the support means being adjustably downwardly convergent adjacent to the discharge opening, releasable means engageable with the adjustably downwardly convergent portions of the support means to retain the same in adjusted position to confine articles therebetween in a pair of downwardly convergent columns, the articles of the separate columns being in vertically staggered overlapping relation and the articles of each column supporting the next adjacent higher articles of the opposite column, substantially horizontally disposed parallel support means mounted in horizontal spaced relation beneath the discharge opening of the compartment adapted alternately to support the

stacks of articles in the compartment and to pass individual articles of the alternate stacks therebetween, and means for oscillating the support means alternately and oppositely between positions in supporting relation to their respective columns and positions retracted therefrom.

4. A vending machine comprising a cabinet, upright support means mounted in horizontal spaced relation in the cabinet defining a compartment therebetween having forward and rearward sides and a lower discharge opening and adapted laterally to confine a plurality of articles having substantially uniform lengths and widths in vertically stacked overlapping relation therein, the support means having lower end portions adjustably downwardly convergent on opposite sides of the discharge opening, releasable means constraining the lower end portions of the support means in adjusted convergent relation to accommodate predetermined widths of such containers with the articles in a pair of downwardly convergent interlocked columns, the articles of the separate columns being in vertically staggered overlapping relation and the articles of each convergent column supporting the next adjacent higher articles of the opposite column; a pair of substantially parallel bars individual to the convergent columns positioned beneath the columns, movable means interconnecting the bars in fixed spaced relation sufficient for the passage of articles to be vended therebetween, and control means connected to the movable means operable to oscillate the movable means and reciprocate the bars alternately and oppositely between positions in supporting relation to their respective columns and positions retracted therefrom.

5. A vending machine comprising a cabinet having a compartment therein; a magazine mounted in the compartment having a pair of upwardly extended walls for confining therebetween a plurality of substantially uniform articles to be vended with the articles horizontally disposed between the walls, the walls being spaced a distance greater than the maximum transverse dimensions of the individual articles; a pair of panels mounted on the walls and downwardly convergent therefrom having lower edges defining a discharge opening therebetween, the panels being spaced a distance greater than the maximum transverse dimensions of the articles stacked between the walls and less than twice said maximum transverse dimensions whereby the panels confine therebetween a pair of downwardly convergent columns of articles, the articles of the separate columns being in vertically staggered overlapping relation and the articles of each column supporting the next adjacent higher article of the opposite column; a pair of substantially parallel bars individual to the columns positioned beneath the columns; movable means mounting and carrying the bars in fixed spaced relation sufficient for the passage of

the articles to be vended therebetween; and control means connected to the movable means for oscillating the movable means and carrying the bars alternately and oppositely between positions in supporting relation to their respective columns and positions laterally retracted therefrom permitting passage of lowermost articles between the bars.

6. A vending machine comprising a cabinet having a compartment therein; a magazine mounted in the compartment having a pair of upwardly extended walls for confining therebetween a plurality of substantially uniform articles to be vended with the articles horizontally disposed between the walls, the walls being spaced a distance greater than the maximum transverse dimensions of the individual articles; a pair of panels pivotally mounted on the walls and downwardly convergently extended therefrom having lower edges defining a discharge opening, means for releasably securing the panels in downwardly convergent relation spaced a distance greater than the maximum transverse dimensions of the articles stacked between the walls and less than twice said maximum transverse dimensions whereby the panels confine therebetween a pair of downwardly convergent columns of articles, the articles of the separate columns being in vertically staggered overlapping relation and the articles of each column supporting the next adjacent higher article of the opposite column; a pair of substantially parallel bars individual to the columns positioned beneath the columns; movable means mounting and carrying the bars in fixed spaced relation sufficient for the passage of the articles to be vended therebetween; and control means connected to the movable means for oscillating the movable means and carrying the bars alternately and oppositely between positions in supporting relation to their respective columns and positions laterally retracted therefrom permitting passage of lowermost articles between the bars.
